(57) **CLAIM**

The ornamental design for a tooth fairy magical box kit as shown and described.

DESCRIPTION

FIG. 1 is a top perspective view of a tooth fairy magical box kit showing my new design.

FIG. 2 is an exploded bottom perspective view of FIG. 1 showing the lid detached from the box.

FIG. 3 is an exploded perspective view of FIG. 1 showing the lid detached from the box.

FIG. 4 is an exploded right perspective view of FIG. 1 showing the lid detached from the box.

FIG. 5 is an exploded top left perspective view of FIG. 1 showing the lid detached from the box.

FIG. 6 is an exploded front perspective view of FIG. 1 showing the lid detached from the box.

FIG. 7 is a second exploded bottom perspective view of FIG. 1 showing the lid detached from the box.

FIG. 8 is an exploded top perspective view of FIG. 1 shown in a first alternate configuration and with the lid detached from the box.

FIG. 9 is an exploded top plan view of FIG. 1 shown in the first alternate configuration and with the lid detached from the box.

FIG. 10 is a second exploded top perspective view of FIG. 1 shown in the first alternate configuration and with the lid detached from the box.

FIG. 11 is an exploded top right perspective view of FIG. 1 shown in a second alternate configuration and with the lid detached from the box.

FIG. 12 is an exploded top right perspective view of FIG. 1 shown in a third alternate configuration and with the lid detached from the box.

FIG. 13 is an exploded top right perspective view of FIG. 1 shown in a fourth alternate configuration and with the lid detached from the box.

FIG. 14 is an exploded top right perspective view of FIG. 1 shown in a fifth alternate configuration and with the lid detached from the box.

FIG. 15 is an exploded top right perspective view of FIG. 1 shown in a sixth alternate configuration and with the lid detached from the box; and,

FIG. 16 is a third exploded top perspective view of FIG. 1 shown in the first alternate configuration and with the lid detached from the box.

The broken lines shown represent portions of the tooth fairy magical box kit that form no part of the claimed design.
